UNITED STATES PATENT OFFICE.

THEODORE A. WEBER, OF NEW YORK, N. Y.

IMPROVED BOTTLE-STOPPER.

Specification forming part of Letters Patent No. 66,270, dated July 2, 1867.

To all whom it may concern:

Be it known that I, THEODORE A. WEBER, of New York, in the county of New York and State of New York, have invented a new and Improved Bottle-Stopper; and I do hereby declare that the following is a full, clear, and exact description thereof, reference being had to the accompanying drawings, making a part of this specification, in which—

Figure 1 is a view of one side of the stopple applied to a bottle. Fig. 2 is another view of the stopple. Fig. 3 is a vertical section through the center of the stopple and its fastenings applied to a bottle. Fig. 4 is a top view of the stopple. Fig. 5 is a bottom view of the stopple, showing the elastic diaphragm.

Similar letters of reference indicate corresponding parts in the several figures.

The object of my invention is to facilitate the filling of bottles with liquids which are highly charged with gas, and which require to be thus preserved for use, by so constructing a movable stopple with an elastic self-closing diaphragm that when secured over the mouth of a bottle a liquid under pressure of gas can be conveniently drawn from a reservoir into the bottle and retained therein without losing its gas, as will be hereinafter described.

To enable others skilled in the art to understand my invention, I will describe its construction and operation.

In the accompanying drawings, *a* represents a sheet-metal cap, which is of a circular form, with its edge turned down so as to form a rim, and with two perforated ears, *g g*, projecting from it, as shown in Figs. 1, 4, and 5. In the center of this metallic cap *a* is a conical depression in the form of a funnel, as shown at *c*, Fig. 3, with a central hole through it, through which the liquid is introduced into the bottle. A circular piece of india-rubber, *b*, is applied to the bottom of the cap *a* and suitably stretched over a ring, *e*, which latter is confined in place by closing the rim of the cap around it, as shown in Fig. 3. Thus the india-rubber diaphragm, the ring, and the cap are secured firmly together.

Surrounding the hole which is through the funnel *c* small holes are made through the rubber diaphragm *b*, as shown in Figs. 3 and 5, through which holes the liquid is forced

into the bottle, when that portion of the diaphragm which closes the opening through the cap *a* is pressed inward. A wire, *h*, is passed through the ears or lugs *g* of the cap *a*, and bent as shown in Figs. 1 and 2; and this wire is fastened to the neck of the bottle *A* by means of a wire, *r*, which latter is so bent around the hooked ends of the wire *h* as to allow the latter to vibrate laterally. Thus, by sliding the stopple upward on wire *h*, the whole can be slipped sidewise from the top or mouth of the bottle. The central portion of the wire *h* is bent in the form of a half-circle, to allow of the insertion, through the funnel *c*, of the delivering-spout of the reservoir containing the liquid under pressure. Another wire, *m*, is so bent as to form an eccentric, as shown, which, in the position of Figs. 1, 2, and 3, holds the stopple firmly upon the top of the bottle, and when turned over, as indicated in dotted lines in Fig. 2, will release the stopple and allow it to be slipped laterally from over the mouth of the bottle. The curved ends *o* of the eccentric should press upon the cap *a* a little on one side of the center, about which they turn, so that the pressure of the gas in a bottle will tend to make said ends hold firmly.

To fill a bottle covered with the stopple the reservoir containing the charged liquid must be provided with a suitable faucet having an india-rubber ring surrounding its nozzle, which will form a tight joint between the outside of the faucet and the stopple; and, furthermore, it would perhaps be desirable to have lateral channels cut into the nozzle of the faucet, through which, when the point or end of this faucet is forced down upon the diaphragm *b*, the fluid can pass laterally and escape into the bottle through the holes which are through the diaphragm; otherwise the force of the fluid must separate said diaphragm from the nozzle of the faucet, and thus find its passage into the bottle. When the point of the faucet is withdrawn the diaphragm will instantly close the opening through the cap *a* by its contraction and the internal force of gas against it. The fluid is drawn from the bottle by pressing down the diaphragm *b*, or by removing the stopple laterally, as before explained.

It will be seen, by reference to Fig. 3, that the india-rubber diaphragm *b* not only serves

to close the hole through the cap *a* by pressing and being pressed against the opening which is through the funnel *c*, but this diaphragm also forms a perfectly tight joint between the cap *a* and the mouth of the bottle to which the stopple is applied.

Having described my invention, what I claim as new, and desire to secure by Letters Patent, is—

1. The combination of the cap *a* and elastic diaphragm *b*, the latter being perforated and applied to said cap, substantially as and for the purposes described.

2. The combination of a perforated cap, *a*, a perforated diaphragm, *b*, and a ring, *e*, when adapted for being held down tight upon a bottle, substantially as described.

3. The cap *a*, diaphragm *b*, with or without ring *e*, stirrup *h*, and eccentric *m*, all combined and adapted to serve the purpose explained.

THEODORE A. WEBER.
